UNITED STATES PATENT OFFICE.

THOMAS J. FLAGG, OF NEW YORK, N. Y., ASSIGNOR TO FISK, CLARK & FLAGG, OF SAME PLACE.

DESIGN FOR A SCARF.

SPECIFICATION forming part of Design No. 15,296, dated August 19, 1884.

Application filed May 3, 1884. Term of patent 7 years.

To all whom it may concern:

Be it known that I, THOMAS J. FLAGG, of the city, county, and State of New York, have invented a new and original Design for a Made-up Scarf; and I do hereby declare that the following is a full and exact description thereof, reference being had to the accompanying drawings, and to the letters of reference marked thereon, making a part of this specification.

My design involves the configuration of the outer apron, S, of the scarf; and it consists, as represented in the drawing, of the two diverging lines, O B C' B', of equal length, drawn each at the same angle from the extremities 15 of the line O C', which defines the lower edge of the scarf, and by two converging straight lines, B A' B' A', of unequal length, which, starting from the extremities B B' of the lines O B, O' B' intersect to form an upper angle, A', 20 upon one side of an imaginary central straight line, x x, drawn midway between the angles B B' to bisect the line O C'.

The form of the lower end of the scarf between the points C C' is not an essential feature of this design, and may therefore be varied to include either a curved line between said points or an angle. (See dotted lines in the drawing.)

The design is completed by the upper line, 30 A' A, drawn from the point A' at a right angle with the central imaginary line, x x, by which it is bisected, and by a straight line, A B, which is of the same length as the opposite line, A' B', and connects the extremity A 35 of said transverse line with the angle B, and by a straight line which extends from the angle A inwardly and intersects the upper line B A', of the apron S at the point D, where said line intersects the imaginary central line, x

x, and defines the center piece, U, and the inner apron, T, of the scarf.

The design may be ornamented and relieved of stiffness or flatness in appearance by means of folds, plaits, or puffs F F, extending inwardly from the side lines, A B A' B', substantially as illustrated in the drawing.

I claim—

1. The design for a made-up scarf, herein shown and described, which consists of the two upper side lines, A B A' B', of unequal 50 length, diverging from the point A', the two lower converging side lines, B C B' C', of equal length united at their lower ends by a transverse line, O C', to define the outline of the outer apron, S, of the scarf, and the upper 55 line, A A', side lines, A B, and inner line, A D, which define the inner apron, T, and center piece, U, of the scarf, and complete its configuration.

2. The design for a made-up scarf, herein shown and described, which consists of the two upper side lines, A B A' B', of unequal 60 length, diverging from the point A', the two lower converging side lines, B C B' C', of equal length, united at their lower ends by a trans- 65 verse line, O C', to define the outline of the outer apron, S, of the scarf, the upper line, A A', side lines, A B, and inner line, A D, which define the inner apron, T, and center 70 piece, U, of the scarf, and complete its configuration, and the ornamentation F F.

In testimony whereof I have signed my name to this specification in the presence of two subscribing witnesses.

THOMAS J. FLAGG.
